UNITED STATES PATENT OFFICE.

SAMUEL LAWRENCE MADDEN, OF LOUISVILLE, KENTUCKY, ASSIGNOR OF
ONE-HALF TO JOHN H. SUMSER, OF SAME PLACE.

HORSESHOE ATTACHMENT.

SPECIFICATION forming part of Letters Patent No. 392,279, dated November 6, 1888.

Application filed March 17, 1888. Serial No. 267,533. (No model.)

To all whom it may concern:

Be it known that I, SAMUEL LAWRENCE MADDEN, a citizen of the United States, residing at Louisville, in the county of Jefferson and State of Kentucky, have invented a new and useful Improvement in Horseshoe Attachments, of which the following is a specification.

The invention relates to improvements in horseshoe attachments, being a secondary shoe so constructed as to be quickly and readily attached to the shoe nailed to the foot, and adapted to prevent the feet of a horse or mule slipping on ice or packed snow in cold weather; and it consists in the construction and novel combination of parts hereinafter described, illustrated in the accompanying drawings, and pointed out in the appended claims.

In the drawings, Figure 1 is a side view of the device attached to the foot of a horse. Fig. 2 is a rear view of the same. Fig. 3 is a plan view of the device detached. Fig. 4 is a reverse plan of the same.

Referring to the drawings by letter, A designates the hoof of a horse, having the shoe B, of ordinary construction, nailed thereto, the said shoe having the central front calk, a, the rear calks, a' a', and the upwardly-standing lug or clip a² above the front calk.

C is the secondary shoe, having the same contour as the fixed shoe and of proper size to fit thereto. The secondary shoe is provided in front with the central upstanding hook, c, that engages over the edge of the lug a² on the fixed shoe, the side lugs, c' c', near the front and at equal distances on each side of said hook, and the rear vertical uprights, c² c², the said lugs and uprights bearing against the adjacent edges of the fixed shoe and preventing the secondary shoe from slipping laterally. The secondary shoe is closed at the rear by the transverse bar c³, which prevents it from spreading.

D is a transverse hollow calk depending from the lower surface of the secondary shoe, into which the calk a is inserted. The calk D has its sides converging downward to form the edge d, which holds upon ice or packed snow.

E are hollow calks into which the calks a' a' are inserted. The said calks are provided

with the holding edges e e, which are not aligned, but incline inward and forward in order to prevent the calks D and E from slipping laterally.

F is a bolt passing through suitable openings in the uprights c² and engaging a nut, f, on the outer side of the adjacent upright. This nut is preferably made octagonal in order to incur less danger of being accidentally disengaged by striking its corners against obstacles in the road.

To secure the secondary shoe in place, the hook c is first engaged over the lug a². The secondary shoe is then turned up to the fixed shoe, and the bolt F, which bears on the fixed shoe in front of the rear calks, is passed through the openings in the uprights and engaged to the nut f.

It is evident that the device can be quickly and readily attached and detached, and that when the horse is stabled the device should be detached to prevent the animal from cutting himself, and, further, to prevent wearing the calks of the secondary shoe dull too rapidly. The use of the device will prevent the keeping idle during winter of a horse that is not furnished with shoes having pointed or sharp-edged calks.

The bar c³, which closes the rear of the shoe, also rests below the bolt F and protects the same. Without this bar some foreign substance—such as stone—might press up between the ends of the secondary shoe and bend the bolt, so that it could not be removed. This would render the shoe valueless.

Having described my invention, I claim—

1. The herein-described secondary horseshoe, consisting of the proper body of the shoe, the depending sharp-edged front and rear calks, D and E, respectively, the hook c, to engage the lug a of the fixed shoe, and the perforated uprights c², in combination with the bolt F, passing through the perforations in said uprights and bearing on the fixed shoe, and the nut f, engaging said bolt, substantially as specified.

2. The herein-described secondary horseshoe, provided with the depending sharp-edged calks D E on its lower surface, and hav-

ing on its upper surface the hook e , the perforated uprights e^2 , and the side lugs, e' , to prevent it from slipping on the fixed shoe, in combination with the bolt F and nut f , substantially as specified.

3. The combination of the fixed shoe B , having the front calk, a , the rear calks, a' , and the upstanding lug a^2 , with the secondary shoe C , having the sharp-edged calks D E , the hook e , the side lugs, e' , and the perforated uprights e^2 , the bolt F , and the nut f , substantially as specified.

4. The combination of the fixed shoe having

calks of ordinary construction and the upstanding lug a^2 , the bolt F , the nut f , and the secondary shoe C , having the uprights e^2 , the hook e , and bar e^3 , closing its rear end and protecting the bolt, substantially as specified.

In testimony that I claim the foregoing as my own I have hereto affixed my signature in presence of two witnesses.

SAMUEL LAWRENCE MADDEN.
